(57) **CLAIM**

The ornamental design for a terminal box for a solar cell module, as shown and described.

DESCRIPTION

FIG. 1 is a front view of a terminal box for a solar cell module in accordance with my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a right side perspective view thereof; and,

FIG. 8 is a top left perspective view thereof.

The broken line shown in the drawing views is unclaimed subject matter and forms no part of the claimed design.
